[57] ABSTRACT

A composite package for holding pressurized fluent materials such as carbonated beverages, beer, aerosols and the like, which includes a thermoplastic container having a hemispherically shaped bottom section with a projection extending outwardly therefrom and a support for holding the container in an upright position having an aperture formed in its end wall through which the projection extends, such that the end wall mechanically engages the projection after insertion so as to attach the support to the container.

PACKAGE FOR HOLDING PRESSURIZED FLUENT MATERIALS

BACKGROUND OF THE INVENTION

This invention relates to a composite package and more particularly to a composite package designed to hold pressurized fluent materials.

Thermoplastic containers for holding pressurized contents have been appearing recently in the prior art. Such containers are desirable because, generally speaking, they are relatively break resistant, light in weight and readily destroyed after use. However, the materials from which such containers are made are rather special in the sense of having to possess a large number of characteristics necessary to accommodate these rather difficult to package contents. Accordingly, such special materials are costly to synthesize and therefore the amount used in each container should be the minimum necessary to allow the container to function satisfactorily, if a profit is to be realized in this phase of the highly competitive plastic packaging industry.

To contain the pressure of the contents, one approach used in the past was to make the container wall thicker but, as mentioned, this is uneconomical. Another approach is to design the container in such a manner as to minimize areas of high stress concentration. As is generally known, the area of highest stress concentration in an elongated container for holding pressurized materials is in the bottom section along the general area of the confluence of the sidewall and the base. As is also generally known, a base section in the form of a hemisphere takes maximum advantage of the strength of the thermoplastic from which the container is constructed since the surface area of such a shape per unit volume is smaller than that of any other base design. Such a hemispherical configuration for a container is disclosed in U.S. Pat. No. 3,480,168. Unfortunately, such a container configuration is incapable of supporting itself in an upright position on a horizontal surface and requires some auxiliary means of support such as the integrally formed feet illustrated in the referenced patent. Such feet, however, though providing some support when accurately shaped, would appear to require rather radical departures from conventional techniques to form. In addition, they support the container at only a few points around its periphery. In copending application Ser. Nos. 75,095 and 75,096, each filed on Sept. 24, 1970, and assigned to the assignee of the present invention, the latter now abandoned, a similar container is shown wherein a separate support member is described which is snapped into a mating depression in the container base or vice versa. Though such a configuration also would appear to function satisfactorily, the departure from a truly hemispherical shape necessary to accommodate the support detracts from the optimum configuration to the extent that such surface protrusions act as stress concentration points in the container base.

SUMMARY OF THE INVENTION

Now, however, there has been discovered a new form of package which overcomes the aforementioned deficiencies of the prior art.

Accordingly it is a principal object of this invention to provide an improved composite package for holding pressurized fluent materials such as beer, carbonated beverages, aerosols and the like.

Another object of this invention is to provide a package of the aforementioned variety wherein the container is provided with a base configuration which minimizes areas of high stress concentration.

5 A further object of this invention is to provide a package of the aforementioned variety wherein the container has an unmodified hemispherical base configuration and is capable of standing in an upright position on a flat surface by means of an auxiliary support member.

10 An additional object of this invention is to provide a package of the aforementioned variety which can be readily formed by conventional molding techniques without the need for any radical change in equipment or in the molding process.

15 Other objects of this invention will in part be obvious and will in part appear hereinafter.

20 These and other objects are accomplished by providing a composite package for holding pressurized fluent materials comprising a one piece thermoplastic container having a substantially hemispherically shaped end section to minimize stresses generated thereon by said fluent materials, said end section having a projection thereon extending away from said container, and means for supporting said container in an upright position which includes an end wall having an aperture therein for accepting said projection such that said end wall engages said projection after insertion so as to attach said supporting means to said container.

25 30 35 The projection preferably has a head portion on its leading end which is greater in cross section than either the remainder of the projection or that of the aperture. The head section is formed after the projection is inserted in the aperture by kissing the protruding end with a hot surface having a temperature above the softening point of the thermoplastic so as to melt and thereby enlarge the protruding end such that it is greater in size than that of the aperture and thereby accordingly cannot be removed therethrough.

BRIEF DESCRIPTION OF THE DRAWINGS

In describing the overall invention, reference will be made to the accompanying drawing wherein:

45 FIG. 1 is a vertical sectional view of a preferred form of package of the present invention in a partially completed stage of assembly;

48 FIG. 2 is a schematic view of the bottom portion of the assembled package of FIG. 1; and

50 FIG. 3 is a perspective view of a portion of an alternative form of container usable as a part of the package of the present invention.

DETAILED DESCRIPTION OF PREFERRED EMBODIMENTS

55 Referring now to the drawing, there is illustrated in FIG. 1, a composite package for holding pressurized fluent materials generally indicated as 10. Package 10 comprises a cylindrical thermoplastic container 12 preferably formed by conventional molding techniques such as by expansion of a tubular parison within closed sections of a partible blow mold. Container 12 is illustrated in FIG. 1 in the shape of a narrow necked bottle wherein the size of the opening at the upper end of the side wall is between 20 to 40 percent of the diameter of the body. Alternatively, however, container 12 may be in the form of a wide mouth can wherein the diameter

of the opening through which the contents is dispensed is basically that of the remainder of the sidewall, as illustrated at 14 in FIG. 3. It should be understood, however, that the size of the container outlet may also be intermediate that shown in FIGS. 1 and 3, as desired. Container 12 is of one piece construction and is formed of a thermoplastic having sufficient strength to withstand pressures, for example of between 20 to 200 psi at wall thicknesses of from 10 to 50 mils. Such thermoplastics are known and include polymers of vinyl chloride and those wherein a major constituent therein has been formed from a nitrile group containing monomer. Container 12 has a substantially hemispherically shaped bottom section 14 which, because of its configuration, minimizes stresses generated thereon as a result of the pressure of the contents. Bottom section 14 has a nub 16 extending outwardly from its otherwise continuous outer surface on the axis of cylindrical container 12. Though nub 16 is of a relatively small size, for example between one thirty-second to one-fourth inch in length and one-sixteenth to one-fourth inch in diameter, satisfactory results may be obtained when nub 16 is in the form of a portion of or all of the tail section conventionally formed in a blow molding operation when the leading end of a thermoplastic parison is clamped between partible mold sections. When package 10 is in assembled condition, nub 16 has a head portion 18 formed in a manner to be described in more detail hereafter which is greater in cross section than the remainder of nub 16.

As a further part of package 10, there is provided a support 20 for holding container 12 in a vertical position on a horizontal surface. Support 20 includes a substantially vertical sidewall 22 and a concave end wall 24 in intimate contact with substantially all of the outer surface 26 of hemispherical bottom portion 14. End wall 24 has an aperture 28 formed therein through which nub 16 projects. Aperture 28 has a cross section which is less than that of nub head portion 18 such that head portion 18 is mechanically engaged with the section of the end wall of support 20 surrounding aperture 28 when the package is in assembled condition.

To assemble container 12 to support 20, container 12 is seated on end wall 24 such that nub 16 projects through aperture 28. A hot plate 29 having a leading surface 30 at a temperature in excess of the softening temperature of the thermoplastic of the container is caused to contact nub 16. Accordingly, nub 16 melts 50 partially and expands in a lateral direction to form head section 18 thereon due to pressure exerted on it by hot plate 29 in the axial direction. Head section 18 after formation is in intimate contact with the outer surface of end wall 24 of support 20 in the manner generally depicted in FIG. 3, such that nub 16 is mechanically interconnected with wall 24 and cannot be removed during normal use of the package. Thus, the manner in which container 12 is attached or secured to support 20 is of a mechanical nature, the surface 30 of hot plate 29 55 as well as the time during which surface 30 is held in contact with nub 16 not being sufficiently great as to cause any substantial melt bonding of nub head section 18 to end wall 24. To avoid surface 30 sticking to nub 16, it may be necessary to coat it with a release agent such as teflon. Though it is necessary for purposes of the invention that the container be made of ther-

moplastic, it is possible for the support to be conveniently formed of any material. Thus, support 20 may be of metal or any other break resistant material or for that matter of a thermoplastic which is relatively inexpensive in comparison with that necessary for the container, for example, low, intermediate or high density polyethylene. Because of the nature of the type of interconnection between the support and the container, it is possible that the thermoplastics of the two parts 10 may be different since compatibility from the standpoint of bonding is not required.

The above description and particularly the drawings are set forth for purposes of illustration only and are not to be taken in a limited sense. Various modifications and alterations will be readily suggested to persons skilled in the art. It is intended, therefore, that the foregoing be considered as exemplary only and that the scope of the invention be ascertained from the following claims.

What is claimed is:

1. A composite package for holding pressurized fluent materials comprising:
  - a one piece container formed of a thermoplastic having sufficient strength to withstand the pressure of a carbonated beverage, said container having a substantially hemispherically shaped end section to minimize stresses generated thereon by said fluent materials, said container having a thickness of between 10 to 50 mils, said end section having a projection thereon extending away from said container said projection having an integral head portion on its leading end; and
  - b. means for supporting said container in an upright position which includes an end wall having an aperture therein for accepting said projection, said head portion being mechanically engaged with a portion of said end wall to attach said supporting means to said container.
2. The package of claim 1 wherein said container is a narrow necked bottle.
3. The package of claim 2 wherein said head portion is mechanically engaged with the inner surface of said end wall.
4. A composite package for holding pressurized fluent materials comprising:
  - a. a container made of a thermoplastic capable of being blow molded, said container having a substantially hemispherically shaped stress minimizing bottom section with a nub extending outwardly therefrom on the axis of said container, said nub having a head portion which is greater in cross section than the remainder thereof;
  - b. a support for said container which includes a substantially vertical sidewall and a concave end wall in intimate contact with the outer surface of said hemispherical bottom section, said end wall having an aperture therein through which said nub projects, said aperture having a cross section which is less than that of the head portion, said head portion of the nub being mechanically engaged with a portion of the end wall of said support surrounding said aperture.
5. The package of claim 4 wherein said support is formed of a thermoplastic which is different from the thermoplastic from which said container is formed.

6. The package of claim 5 wherein said support is formed of low density polyethylene.
